R. B. WARE

BEAM COMPASS

Filed March 18, 1926

INVENTOR.

Rodney B. Ware.

BY

Frank A. Cutler,
ATTORNEY.

UNITED STATES PATENT OFFICE.

RODNEY B. WARE, OF WADSWORTH, OHIO.

BEAM COMPASS.

Application filed March 18, 1926. Serial No. 95,752.

My invention relates to improvements in beam-compasses, and consists essentially and generally of certain peculiar rods, clamps, and implement holders, forming 5 peculiar combinations, together with such other parts and members as may be necessary or desirable in order to render the instrument complete and serviceable in every respect, all as hereinafter set forth.

10 One object of my invention is to produce a comparatively light (in weight), compact, and inexpensive, yet strong and durable, beam-compass, which is capable of convenient, quick, and accurate adjustment for different uses and purposes, and has a wide range of application.

Another object is to provide such an instrument with means for utilizing practically any ordinary pencil, ruling-pen, or 20 scribe, thus obviating the need of furnishing special implements for marking purposes.

Still another object is to furnish the beam-compass with a convenient and improved holder for the centering spurs.

A further object is to afford means, in a beam-compass, whereby the movable parts and members not only can be adjusted easily and quickly, but after adjustment can be held securely and so as not to slip.

Nearly all of the parts and members of this instrument are interchangeable, which is an obvious advantage.

Other objects and advantages will appear 35 in the course of the following description.

I attain the objects and secure the advantages of my invention by the means illustrated in the accompanying drawings, in which—

40 Figure 1 is a front elevation of a beam-compass which embodies a practical form of my invention, intermediate portions of the beams or rods being broken out to economize space; Fig. 2, a top plan of said beam-compass, but with the parts and members disposed as in the following view, intermediate portions of the rods being again broken out, and also in the next view; Fig. 45 3, a front elevation, with parts in section, of the instrument, the spur holder being here clamped to the lower rod, while in the first view said holder is clamped to the upper rod; Fig. 4, an elevation of the outer

end of the lower rod, showing the marking-implement holder secured thereto by a 55 clamp, which clamp and holder are in partial section; Fig. 5, a side elevation in partial section of the spur holder; Fig. 6, an end elevation of said last-named holder, and, Fig. 7, an opposite end elevation 60 thereof.

Similar reference characters designate similar parts throughout the several views.

This beam-compass comprises upper and under beams, bars, or rods 1 and 2, respectively, two rod clamps and two implement holder clamps, a spur holder, and a marking-implement holder, all of which are described in detail below.

The rods 1 and 2 are generally cylindrical, 70 and in such case the upper rod is chamfered on top, as represented at 3, and the lower rod is chamfered on the bottom and back side, as respectively represented at 4 and 5. The outer terminal of the rod 2 is bent rearwardly and then continued a short distance in parallel relation with the main portion of said rod to form an arm 6. In the present example inch scales are delineated on the front sides of the rods 1 and 2, starting 75 with "0" near the outer terminal of the upper rod, and ending with "17" near the inner terminal thereof, and starting with "1" on the lower rod some distance from the bent terminal thereof, and ending with "9" near the 80 opposite terminal; and a fractional inch scale is delineated on top of the arm 6, as clearly shown in Fig. 2.

The above-mentioned clamps are alike except that in each of the members thereof 90 which receive the rods 1 and 2 are two parallel openings therethrough for that purpose, while in each of the members thereof which receive one or the other of said rods or the arm 6 and one of the implement holders are 95 two openings therethrough arranged at right-angles to each other. Otherwise a description of one clamp applies to all. Each clamp consists in part of a cylindrical slide 100 7 or 8, the former having the parallel openings therein, one above the other, for the rods 1 and 2, and the latter having the openings therein, one above the other, which are at right-angles to each other and adapted to receive either of said rods, the arm 6, and 105 the part of either of the implement holders

that is made especially to fit one or the other of said openings. Both slides 7 are arranged vertically on the rods 1 and 2, one of the slides 8 is arranged vertically on the arm 6, with said arm passing through the lower opening in said last-named slide, and the other slide 8 is arranged horizontally on one or the other of said rods, with the rod in the rear opening.

10 In addition to the slide 7 (or 8), each of the aforesaid clamps consists of a pair of gripping rings 9, a pair of springs 10, and a pair of knurled nuts 11. Each slide at each end is turned down, as represented at 15 12, to form a centering part for one of the rings 9, and a screw-threaded projection 13 extends from such end to receive one of the nuts 11. The openings through the slides 7 and 8 cut into the reduced or centering parts 20 12 of said slides at both ends, and the rings 11, when bearing on the rods and other parts in said openings, are so held thereby that they project beyond the outer end surfaces of said parts. The springs 10 are centrally 25 perforated to receive the projections 13, and of a size to bear on the outer sides of the rings 9. It follows, therefore, that when the nuts 11 are screwed inwardly on the projections 13, said nuts force the springs 10 30 against the rings 9 and the latter against the rods and other parts extending through and projecting from the openings in the slides 7 and 8, and thereby cause said slides to grip tightly said rods and other parts, and 35 all of these parts and members to be securely clamped together. Release of the parts is effected simply by loosening the nuts 11.

To relatively adjust the rods 1 and 2 it is preferable to loosen the upper nut 11 of 40 the left-hand rod clamp and the lower nut 11 of the right-hand rod clamp, leaving the other two nuts of said clamps tight. The rods can now be moved independently of each other endwise to whatever extent may 45 be desired, within the limit of the instrument. After adjustment the loose nuts are retightened.

To remove the left-hand clamp slide 8 from the corresponding end of the upper rod 50 1 (Fig. 1) and place it on the lower rod 2 (Figs. 2 and 3), it is necessary, after taking said slide from the upper rod, to loosen both nuts 11 on the left-hand slide 7 and remove said slide from both rods, and then to place 55 said first-named slide on said lower rod, said second-named slide on both rods, and retighten said nuts.

The spur holder, of which mention has 60 been made, comprises a round rod 14, of approximately the same diameter of either of the rods 1 and 2, which has a knurled head 15, and is bored and split at the ends substantially as shown, the slits in the upper and lower terminals being respectively indicated by the numerals 16 and 17, and the

upper and lower bores or chambers by the numerals 18 and 19. At 20 is represented a spur which is in the chamber 18, and at 21 is represented a spur which is in the chamber 19. The chamber 18 is in the axial center of the holder 14, while the chamber 19 is eccentrically situated therein.

The spur 20 is of a size and shape to fit within either chamber 18 or 19, so also is the spur 21. The spur 20 is for use in marking metal, while the spur 21 is for centering the instrument when employed in drawing on paper. Either spur may be readily substituted for the other in operative position, the one not in use being stored in the upper chamber 18. The split terminals of the holder 14 function in the customary manner for holding the spurs in place. Each spur has notches 22—22 therein adjacent to the ends thereof, for the insertion of the thumbnail to facilitate withdrawing the spur from its chamber. At the inner end of each chamber 18 and 19 is an extension 23 of less diameter than the chamber into which it opens, to receive and prevent injury to the point of the spur inserted in the chamber. In Fig. 3 the point of the spur 20 is shown projecting into the extension 23 from the chamber 18; in a similar manner the point of the spur 21 is received in said extension when said last-named spur is placed in said chamber, after withdrawing said spur 20 for insertion in operative position in the chamber 19. When the spur in the chamber 19, which ever it may be, is not in use, the same can be reversed in said chamber to locate its point in safety in the extension 23 from said chamber.

While the nut 11 at the forward terminal of the left-hand clamp slide 8 is loose, the holder 14 is slipped into the vertical opening in said slide and adjusted, and then said nut is retightened to secure said holder firmly in place.

The holder 14 is not only capable of vertical adjustment, but also of adjustment on its axis for the purpose of locating the spur in the eccentrically-disposed chamber 19 at exactly the right distance from the associated marking implement. In other words, the eccentrically-located chamber and the provision for rotatably adjusting the holder 14 enable said spur to be very finely adjusted.

The marking-implement holder, of which mention has been made, comprises a yoke or bifurcated abutment head 24 having at the rear end a shank 25 that fits the upper opening in the right-hand clamp slide 8. This slide is mounted on and secured to the arm 6, and the shank 25 is at right angles to said arm. The diameter of the shank 25 is approximately the same as that of the rods 1 and 2, or of the holder 14, and said shank is hollow. The head 24 opens through the sides and front end thereof, and in the front

edges of the top and bottom of said head are notches, as indicated at 26 in Fig. 2. The shank 25 may be adjusted lengthwise and about its axis in the upper opening in the 5 right-hand slide 8, and after adjustment is securely clamped in position by means of the nut 8 on the top of said slide. A draw head 27 is slidably arranged in the abutment head 24, and the former has at the rear end 10 a shank 28 that extends through the rear end of said abutment head and through the hollow shank 25 to receive a nut 29 behind said hollow shank, said first-named shank being screw-threaded at its rear terminal to 15 accommodate said nut. The head 27 may be projected forward of the notched ends of the head 24, and in said first-named head is a vertical opening or hole 30 to receive a scribe, drawing-pen, or other marking implement, such as a pencil 31. The pencil 31 is first passed down through the hole 30, and then the nut 29, which is on the shank 28, is rotated on said shank in the direction to force said nut against the rear end of 25 the shank 25 and draw said first-named shank rearwardly and with it the head 27. When thus drawn forcibly rearwardly by the nut 29, the head 27 forces the pencil 31 into the notches 26 in the head 24. In this 30 manner and by this means the pencil is held firmly in place, but may be released for removal by loosening the nut 29. Any desired angle may be given to the pencil by partially rotating the shank 25 in its slide 8, after 35 loosening the nut 11 on top of said slide 8, said nut then being tightened again.

The implement holders are, of course, located on the same side of the rods 1 and 2, and the arm 6 is provided for the purpose 40 of positioning the marking-implement holder approximately in the vertical plane with the spur holder which is parallel with the vertical plane of said rods. Otherwise the marking implement would be located 45 much to far from the rods 1 and 2, and out of proper relation to the spur, or else it would be necessary also to locate the spur holder too far from said rods.

Upon referring to Fig. 2 it will be seen 50 that the marking-implement-holder clamp is set at $\frac{15}{16}$ ". For resetting purposes this clamp should be moved to the left into the position indicated by the dotted lines 32, where the clamp registers with the first 55 scale mark on the arm 6.

If the spur-holder clamp is on the top rod 1, as when a long radius is required, it is placed at "0," and the left-hand rod clamp is placed at the last mark on the lower rod 2. The reading in inches is now 60 taken from the upper rod, as "11," the same being the sum of the nine inches on the lower rod and the two inches beyond on the upper rod. For any additional fraction of an inch required, move the implement clamp 65

on the arm 6 to the right until said clamp registers with the proper fraction mark on said arm, as $\frac{15}{16}$ ".

In Fig. 1 the pencil 31 is shown tilted in such a manner as to enable the point 70 thereof to mark close up in a corner.

To set the instrument for a shorter radius and with the spur-holder clamp mounted on the lower rod 2, slide said clamp on said rod until the clamp registers with some inch 75 mark thereon, partially rotate the spur-holder 14, or the shank 25, or both, to adjust the operative spur and marking-implement points, either or both, to a full number of inches, employing for the purpose 80 any scale at hand, such as the top rod 1, which may be detached for such purpose if desired. Then set the spur-holder clamp on the desired inch mark, and, if a fraction more be needed, set the marking-implement-holder clamp 85 on the required scale mark on the arm 6.

After the required adjustments have been made in any given case, the beam-compass is used in a similar manner to any other instrument of the kind. 90

The chamfered or flattened parts 3, 4, and 5 of the rods 1 and 2, serve the usual purpose of assisting in preventing the parts and members clamped thereto from turning 95 thereon.

More or less change in the shape, size, construction, and arrangement of some or all of the parts and members of this instrument may be made, without departing from the 100 spirit of my invention or exceeding the scope of what is claimed.

What I claim as my invention, and desire to secure by Letters Patent, is—

1. In a beam-compass, rods, and clamps 105 mounted on and connecting said rods, each of said clamps comprising a slide perforated to receive said rods, and having at the ends centering parts and threaded extensions, gripping rings centered by said parts 110 and arranged to bear on said rods, nuts on said extensions, and springs interposed between said rings and said nuts.

2. In a beam-compass, rods, clamps mounted on and connecting said rods, other 115 clamps mounted on said rods, and implement holders carried by said last-named clamps, each of said first-named clamps comprising a slide perforated to receive said rods, and each of said second-named clamps 120 comprising a slide perforated to receive either of said rods and either of said holders, and each of said clamps comprising, further, gripping rings adapted to bear on said rods or one of said rods and a part of 125 one of said holders, nuts, and springs interposed between said rings and said nuts, each slide having at the ends centering parts for said rings, and threaded extensions for said nuts. 130

3. In a beam-compass, rods one of which is bent at one terminal to form an arm parallel with the main part of the rod, adjusting clamps for said rods, an implement holder, means to support said holder from said rods, and an implement holder adjustably supported from said arm.
4. In a beam-compass, rods one of which is bent at one terminal to form an arm parallel with the main part of the rod, adjusting clamps for said rods, an implement holder, means to support said holder in front of said rods, and an implement holder adjustably supported from said arm in a vertical plane with said first-named holder, which plane is approximately parallel with the vertical plane of said rods.
5. In a beam-compass, rods one of which is bent at one terminal to form an arm parallel with the main part of the rod, clamps mounted on and connecting said rods, another clamp adapted to be mounted on either of said rods, an implement holder attachable to said last-named clamp, still another clamp adapted to be mounted on said arm, and an implement holder attachable to this clamp, said clamps comprising slides some of which are perforated to receive said rods and others to receive said rods and parts of said holders, and having at the ends centering parts and threaded extensions, gripping rings centered by said centering parts and arranged to bear on said rods and on said parts of said holders, nuts on said extensions, and springs interposed between said rings and said nuts.
6. In a beam-compass, rods, adjustable clamping means therefor, a transversely perforated slide adapted to be mounted at one terminal on and secured to either of said rods, a spur, a holder chambered to receive said spur, and receivable in the perforation in said slide, and clamping means mounted on the other terminal of said slide to bear on said holder, whereby the latter can be adjusted when said clamping means are loosened.
7. In a beam compass, rods, adjustable clamping means therefor, a transversely perforated slide adapted to be mounted at one terminal on and secured to either of said rods, spurs, a holder having therein eccentric and axial chambers opening through the ends thereof for said spurs, and receivable in the perforation in said slide, and clamping means mounted on the other terminal of said slide to bear on said holder, whereby the latter can be adjusted when said clamping means are loosened.
8. In a beam-compass, rods, adjustable clamping means therefor, spurs, a holder having therein eccentric and axial chambers for said spurs, said chambers opening through opposite ends of said holder, and the latter being split to afford gripping means for said spurs, and means to clamp said holder to either of said rods, and capable of being loosened to permit said holder to be rotated on its axis.
9. In a beam-compass, spurs, a holder having chambers therein opening through opposite ends thereof for said spurs, said chambers at their inner ends being extended to form receptacles of smaller diameters than the chambers to receive the points of said spurs.
10. The combination, in a beam-compass, with rods, and adjustable clamping means therefor, of a spur, a holder chambered to receive said spur, a slide perforated to receive either of said rods and said holder, said slide having end centering parts and threaded extensions, gripping rings centered by said parts and adapted to bear on the rod and holder in the perforations in said slide, nuts on said extensions, and springs interposed between said rings and said nuts.
11. In a beam-compass, a rod, a clamp mounted on said rod, and an implement holder supported by said clamp, said holder comprising a recessed abutment head provided with a hollow shank, a draw head in said abutment head and provided with a shank which extends through said hollow shank, and a nut on said draw-head shank behind said hollow shank.
12. In a beam-compass, a rod, a clamp mounted on said rod, and an implement holder supported for rotary adjustment by said clamp, said holder comprising a recessed abutment head provided with a hollow shank, a draw head in said abutment head and provided with a shank which extends through said hollow shank, and a nut on said draw-head shank behind said hollow shank.
13. In a beam-compass, a rod, a clamp mounted on said rod, and an implement holder supported by said clamp, said holder comprising a bifurcated abutment head having notches in the front ends of the parts of the bifurcation, and provided with a hollow shank, a perforated draw head in said abutment head and provided with a shank which extends through said hollow shank, and a nut on said draw-head shank behind said hollow shank, the construction and arrangement of parts and members being such that an object in said draw head may be forced into close contact with the notched end of said abutment head.
14. The combination, in a beam-compass, with a rod, of a perforated slide mounted on said rod, a bifurcated head provided with a hollow shank passing through the perforation in said slide, the latter having a centering part and a threaded extension, a gripping ring centered by said part and arranged to bear on said shank, a nut on said extension, a spring interposed between said ring

and said nut, a draw head slidably arranged in said bifurcated head and provided with a shank which extends through said hollow shank, and a nut on said draw-head shank ¹⁵ behind said hollow shank.

15. The combination, in a beam-compass, with a rod, of a perforated slide mounted on said rod, a spur holder passing through the perforation in said slide, the latter having ²⁰ a centering part and a threaded extension, a gripping ring centered by and arranged

to bear on said holder, a nut on said extension, and a spring interposed between said ring and said nut.

16. In a beam-compass, rods, slides transversely perforated to receive said rods, and clamping means mounted on the terminals of said slides to bear on said rods and rigidly secure said slides and rods together when said clamping means are tightened, the latter ¹⁵ ²⁰ consisting in part of resilient members.

RODNEY B. WARE.
